Primary Examiner — Richard Kearney

(57) **CLAIM**

The ornamental design for decorative panel for building, as shown and described.

DESCRIPTION

The patent or application file contains at least one drawing executed in color. Copies of this patent or patent application publication with color drawing(s) will be provided by the Office upon request and payment of the necessary fee.

1.-3. Decorative panel for building

1.1 Side perspective view

1.2 Font view

1.3 Front perspective view

2.1 Side perspective view

2.2 Rear perspective view

2.3 Front view

2.4 Front perspective view

3.1 Front view

3.2 Top perspective view

3.3 Bottom perspective view

1.1-1.3 show the decorative panel for building with a portion of the front panel removed for ease of illustration, 2.1-2.4 show the decorative panel for building with a portion of the front panel and substrate removed for ease of illustration and 3.1-3.3 show the decorative panel for building with the complete front panel as claimed. The plants shown in the drawings are environmental and form no part of the claimed design.

1 Claim, 10 Drawing Sheets

(10 of 10 Drawing Sheet(s) Filed in Color)
